UNITED STATES PATENT OFFICE.

WILLIAM JAMES McKIMMEY, OF BARNETT, ILLINOIS.

SCREW-CONNECTING DIE AND STOCK.

No. 812,075.

Specification of Letters Patent.

Patented Feb. 6, 1906.

Application filed March 23, 1905. Serial No. 251,646.

To all whom it may concern:

Be it known that I, WILLIAM JAMES Mc-
KIMMEY, a citizen of the United States, re-
siding at Barnett, in the county of Montgom-
5 ery and State of Illinois, have invented new
and useful Improvements in Screw-Connect-
ing Dies and Stocks, of which the following is
a specification.

This invention relates to screw-threading
10 dies and stocks, and has for its object to pro-
vide a construction wherein the dies are con-
veniently adjustable to operate upon differ-
ent sizes of work and wherein ratchet means
15 are provided to enable the threading oper-
ation to be carried out by an oscillatory mo-
tion of the stock in either direction.

The preferred embodiment of the inven-
tion is illustrated in the accompanying draw-
ings, in which—

20 Figure 1 is a side elevation of a die-stock
embodying my improvements. Fig. 2 is a
longitudinal section of the same, taken on the
line 2 2 of Fig. 3. Fig. 3 is a longitudinal sec-
25 tion taken on a plane at right angles to Fig. 2,
and Fig. 4 is a cross-section through the die-
holder and its containing-collar on the line 4
4 of Fig. 3.

Referring now more particularly to the
drawings, the numeral 1 designates a die-
30 stock of ordinary form and construction, ex-
cept as hereinafter described, the same being
provided with the usual oppositely-project-
ing arms 2, having threaded sockets 3 to re-
35 ceive the threaded inner terminals of oper-
ating-handles 4. These handles are provided,
preferably, with openings or recesses 5 for
the reception of a suitable tool to facilitate
their application and removal.

In the bore of the stock 1 is fitted a tubu-
40 lar rotary die-carrier 6, which is provided
with a ratchet-tooth ring 7, which may be in-
tegral therewith or formed independently
thereof and fastened thereto by suitable se-
curing devices, such as screws 8. This ring
45 is mounted for rotation between the side
members of the stock 1 and is adapted to im-
part rotary motion to the carrier 6. One end
of the carrier 6 receives a bushing 9, provided
with a bore of properly-restricted diameter
50 to hold and center the part which is to be
threaded, and this bushing is provided at its
outer end with a flange 10, which abuts
against one end of the carrier and the adja-
cent side of the stock. The other end of the
55 carrier projects beyond the stock and has fit-
ted thereon a collar or cuff 11, which is re-

movably fastened thereto by screws 12. This
collar forms a chamber for the reception of a
die-holding ring 13, which is removably fas-
tened therein by screws 14, said screws being 60
adjustable in longitudinal slots 14' formed in
the carrier to adapt the holding-ring 16 to
be adjusted toward and from the stock. In
diametrically opposite sides of the ring are
formed sockets 15, which receive oppositely- 65
arranged taps or dies 16, which are adjust-
able therein by means of adjusting-screws 17,
working in threaded openings in the ring, so
as to enable the dies to be radially adjusted
to suit the size of the work which is to be 70
threaded thereby. The screws 17 are ar-
ranged to slide in slots 17' formed in the car-
rier to permit the carrier-ring 16 to have free
movement when adjusted through the ac-
tion of the screws 14 toward and from the 75
stock. This adjustability of the carrier-ring
toward and from the stock is of prime im-
portance. The tool is especially adapted
and has been designed for threading extre-
mities of irregular bolts, such as staple bolts or 80
forks fixed in close places and which vary to
some extent in length. By making the car-
rier-ring adjustable toward and from the
stock the ring is adapted to be positioned for
threading the shanks of bolts of this character 85
which vary in length, thus enabling bolts to
be conveniently threaded where the stock as
a whole cannot be adjusted for operating
upon very short bolts. Where the bolt pro-
jects from a wall or other surface and the 90
bushing 9 abuts against the wall, it will be
readily understood that the adjustability of
the carrier-ring renders the device exceed-
ingly useful in threading the shanks of short
bolts, since the wall will prevent the adjust- 95
ment of the stock bodily to project the bolts
to the desired extent through the tool.

One of the arms 2 of the stock is formed
with a chamber or recess 18, closed by a suit-
able form of cover-plate 19. In this cham- 100
ber are arranged pawls 20 and 21, which are
pivotally mounted for lateral movement on
the arm and are adapted to be thrown into
engagement with the ratchet-ring 7 by means
of an interposed coil-spring 22. These pawls 105
are provided with oppositely-arranged oper-
ating portions to engage the ratchet-teeth
and respectively control the movement of the
ratchet-ring in opposite directions. Between
the pivoted and free ends of the pawls is a 110
sliding retractor-block 23, which is adjust-
able by means of a set-screw 24, which screw

has its shank projecting to the exterior through a transverse slot 25, formed in the cover-plate 7, with its head arranged to bind against the outside of said cover-plate. By means of this screw the block 23 may be adjusted in one direction or the other to move one of the pawls out of engagement with the ratchet-ring and to permit the other to be thrown into engagement therewith by means of the spring 22, the block being fastened in adjusted position by tightening up the screw. By this means the pawl-and-ratchet mechanism may be operatively connected to permit the rotary carrier to be intermittently rotated to the right or left while the stock is being continuously oscillated and to prevent retrograde movement of the carrier during the reverse or backward movement of the stock. Right or left threading may therefore be accomplished with equal ease by a continuous oscillatory movement of the stock, thus doing away with the necessity of rotating the stock entirely about its axis or changing the positions of the parts for such adjustment.

From the foregoing description, taken in connection with the accompanying drawings, the construction and mode of operation of the invention will be understood without a further extended description.

Changes in the form, proportions, and minor details of construction may be made within the scope of the invention without departing from the spirit or sacrificing any of the advantages thereof.

Having thus described the invention, what I claim as new is—

1. In a threading-tool, the combination of a stock, a rotary carrier held by the stock,

40 said carrier being provided with sets of longitudinal slots, a holding-ring within the carrier, adjusting-screws connecting the ring to the carrier and adjustable in one set of slots to permit the ring to be adjusted toward and from the stock, radially - adjustable dies mounted in the carrier-ring, screws carried 45 by the carrier-ring for radially adjusting said dies, said screws being adjustable in the other set of slots in the carrier, and means for rotating the carrier.

2. In a threading-tool, the combination of 50 a stock provided with a chamber in one of the arms thereof, a cover for said chamber provided with a transverse slot, a rotary die-carrier held by the stock, said carrier being provided with ratchet - teeth, pivoted pawls 55 mounted within the chamber and provided with portions to engage the ratchet-teeth to rotate the die-carrier in opposite directions, a spring arranged between and acting on said pawls to normally throw them into engagement with the ratchet-teeth, a transversely-sliding block arranged within the chamber and adapted to be adjusted in one direction or the other to throw the pawls alternately into and out of operation, and an adjusting 60 member connected with the block and projecting exteriorly through and movable in the transverse slot in the cover, said adjusting member comprising a screw, whereby the block may be clamped in adjusted position. 70

In testimony whereof I affix my signature in presence of two witnesses.

WILLIAM JAMES McKIMMEY.
